firm composed of Moise Elias and Edward Keller

Application June 13, 1947, Serial No. 139,660

Term of patent 7 years

(Cl. D20—4)

To all whom it may concern:

Be it known that I, Edward Keller, a citizen of the United States of America and resident of Forest Hills, county of Queens, and State of New York, have invented a new, original, and ornamental Design for a Brassière, of which the following is a specification, reference being had to the accompanying drawing, forming a part thereof, in which

Fig. 1 is a front view of a brassière embodying my design; and

Fig. 2 is a rear view of the brassière shown in Fig. 1.

I claim:

The ornamental design for a brassière, as shown.

EDWARD KELLER.
